CENTRALIZED TRAFFIC CONTROLLING
SYSTEM FOR RAILROADS

William D. Hailes, Brighton, N. Y., assignor to
General Railway Signal Company, Rochester,
N. Y.

Application June 1, 1936, Serial No. 82,711

30 Claims. (Cl. 246—3)

This invention relates to centralized traffic controlling systems for railroads and it more particularly pertains to a means for transmitting and registering controls and indications in a communication system of the multiple impulse or code type.

The switches and signals are distributed throughout the territory in such a system and those located relatively near or adjacent each other, together with the apparatus provided to govern these switches and signals, are conveniently referred to as comprising a field station. The communication system is provided to inter-connect the control office with the several field stations and it is so organized that complete control and supervision of the various switch and signal devices at the remote stations are obtained by the operator. Such a traffic controlling system is supplemented by the usual automatic block signal system and other local means ordinarily provided to guard against unsafe train movements, improper operation of track switches and the like.

In accordance with the present invention, the communication system comprises a two-wire line circuit extending from the control office through the several field stations in series. The conductors of this line circuit are conveniently referred to in the drawings as line conductor L and return conductor R. This two-wire line circuit is normally energized from a source of current located in the control office, with the line relays and other devices connected in series with the line wires at the field stations and with the line and return conductors permanently connected together at the end station to form a closed circuit loop.

The line circuit is so arranged that any field station in the series may initiate the communication system into a cycle of operations, during which indications are transmitted from the initiating field station to the control office. These indications comprise multiple impulses making up a code combination, which effects the registration of the transmitting field station in the control office and the transmission of indications in accordance with track and signal conditions at the transmitting station.

The line circuit is also arranged so that the control office may initiate the operation of the communication system, during which multiple impulses are transmitted making up a code which is effective to select a desired station and to transmit controls thereto.

The system is of the duplex type, that is it is operated through separate cycles of operation,

during each of which transmission of controls and/or transmission of indications may occur. When controls are transmitted, a station selective code is first applied to the line circuit for selecting the particular station with which communication is desired and then the controls are transmitted to that station. Similarly, when indications are transmitted the particular field station transmitting such indications first transmits a station registering code for identifying this station in the control office and then the indications are transmitted from this station to the control office.

For the transmission of controls, a predetermined number of impulses of selected polarities are applied to the line circuit, each impulse operating step-by-step apparatus in the control office and at the field stations through a cycle of operation, irrespective of the character of the impulses. The time spaces between successive impulses are varied in length in accordance with the controls to be transmitted so that these time spaces are comparatively long or short and they are combined with the polar impulses to make up the code for selecting stations and for transmitting controls thereto.

For the transmission of indications, the impulses themselves are varied in length to provide normally long impulses or abnormally short impulses at each step of the stepping mechanism. In addition to the variation in length of impulses, alternating current is applied to the line circuit, both during the impulse periods and the time spaces between impulse periods for providing additional selections for indication transmission. This feature of applying or superimposing alternating current on the line circuit for the purpose of transmitting indications over a stepping circuit transmitting stepping impulses of direct current is broadly shown in Fig. 4 of the prior application of Hailes and DeLong Ser. No. 526,674 filed March 31, 1931, and no claim is made herein to any invention disclosed in said prior application. Briefly the indication codes comprise short or long impulses, alternating current or no alternating current superimposed on the line circuit during the impulse periods and alternating current or no alternating current superimposed on the line circuit during the time space periods.

For convenience in describing the operation of this system the energized or impulse periods from the control office source of direct current will be referred to as the "on" periods and the deenergized or time spaces between direct current im-

levers. Similarly, one or more signal control levers may be provided, but for convenience no signal lever is illustrated, since the control of switches by the illustrated switch levers is typical of the control of signals when signal levers are provided.

5 A single OS indicating lamp is illustrated for the purpose of indicating the method of transmitting an OS indication from a particular field station and it will be understood that additional lamps of this type may be provided as required.

10 A plurality of code jumpers are selected by the circuits controlled by the CD relays and those illustrated by reference characters 10 and 11, selected by the illustrated CD relay in Fig. 1C, are for the purpose of applying a station selecting code to the line circuit in response to the initiation of the operation of the system when the CD relay is picked up.

15 20 Code sending relays PC and NC are for the purpose of providing the proper polarity of energization of the line circuit during the transmission of control impulses. With relay PC energized and relay NC deenergized a (+) impulse is applied to the line circuit from battery LB when the impulsive relays effect the closure of the line circuit. With relay PC deenergized and relay NC energized, then a (-) impulse is applied to the line circuit upon the closure of the line circuit by the impulsive relays. Code sending relay LG is for the purpose of rendering a time space comparatively long in duration, when this relay is picked up. If relay LG is not picked up at a particular step of the cycle, then the 25 time space is comparatively short in duration.

30 35 Pilot relays 1PT to 4PT inclusive are polar relays of the magnetic stick type and are positioned in accordance with a station identifying code received in the control office during a duplex cycle or a cycle during which indications alone are being transmitted. A polar relay of the magnetic stick type operates its contacts to normal and reverse positions in response to current of normal and reverse directions respectively through its 40 45 winding and the contacts are magnetically maintained in their last operated position after the winding is deenergized. Relays MF, MFZ, and MBZ are the indication code receiving relays which are conditioned during the steps of a cycle 50 55 during which indications are transmitted. Relay MF registers the length of the "on" indication at each step, relay MFZ registers whether or not alternating current is superimposed on the line circuit during the "on" period at each step and relay MBZ registers whether or not alternating current is superimposed on the line circuit during the "off" period at each step.

60 Impulse relays 1E to 5E, inclusive, are for the purpose of timing the closure and opening of the line circuit during a cycle of operations. Relay OC is a cycle controlling relay, being picked up at the start of any cycle and maintained picked up until the end of the cycle, the purpose of which will be pointed out later in the description.

65 Line relay F is included in the line circuit at the control office and is for the purpose of repeating each energization and deenergization of the line from battery LB, irrespective of the polarity of such energization. Line repeating relay FP repeats each energization of relay F after a cycle of operations is initiated, but does not repeat the normal energization of line relay F when the system is in its condition of rest.

70 75 Slow-acting relays SA, SB, and SD are picked up

at the beginning of each cycle, remain up throughout the cycle and are dropped at the end of the cycle. Relay SC is normally picked up, is dropped out at the beginning of each cycle and again picked up during the "clearing out" period at the end of each cycle. Relay SC has such characteristics that its pick-up time is relatively long compared with the pick-up time of quick-acting relays such as relay FP and the drop-away time of relay SC is likewise comparatively long.

80 85 Associated with the line repeating relays is a bank of stepping relays, including relays 1V, 2V, 3V, together with a half-step relay VP. This bank of stepping relays is for the purpose of marking off the successive steps of each cycle, the stepping relays being successively picked up during the "off" periods and relay VP being shifted in position during each "on" period.

90 95 Control cycle relay C is provided for marking a cycle of operations for the transmission of controls, this relay being picked up during the initiating period of a control cycle and remaining up until the "clearing out" period at the end of such a cycle. Field station control relay CF is for the purpose of marking a cycle of operations for the 100 transmission of indications, this relay being picked up during the initiating period of a cycle for the transmission of indications and remaining up until the "clearing out" period of such a cycle. During a duplex cycle, when controls and 105 indications are both being transmitted, relays C and CF are both picked up. Relay FPA repeats the deenergized conditions of relay FP, that is, relay FPA is picked up during each deenergization of relay FP and is dropped out at each energization of relay FP, during a cycle of operations.

110 A vacuum tube detecting device is illustrated in the upper portion of Fig. 1B and is for the purpose of detecting alternating current impulses superimposed on the line circuit and for translating these impulses into direct current impulses for operating the MFZ and MBZ relays in a manner which will be fully described. This detecting device comprises vacuum tubes 1VT and 2VT with their associated in-put transformers 1IT and 2IT respectively. Out-put transformer 1OT in the out-put of tube 2VT has its secondary connected to the MBZ and MFZ relays through rectifiers 1RC and 2RC. Various resistances, inductances and condensers are included in the line 115 120 and vacuum tube circuits, the purpose of which will be evident from the following description. It is assumed that the filaments of the vacuum tubes are energized from a source of battery AB and the plates are energized from a source of battery BB, although it will be obvious that a power transformer may be used for energizing these tube circuits by the usual rectified current arrangement if desired.

125 130 *Field station equipment.*—The field station illustrated in Figs. 2, 2A, and 2B is typical of all stations of the system and may be adapted for use at the first, second or any other location by merely altering certain code jumpers to arrange for the desired codes. For convenience in the description, this field station has been specifically illustrated as being the first of the series by reason of the distinctive exponents employed. Likewise the end station illustrated in Fig. 2B is 135 assumed to be the second in the series by reason of the distinctive exponents employed, but it will be understood that other stations may be interposed between the control office and the first station and between the first station and the second station.

A track section is illustrated in Fig. 2B, having track switches 1TS and 2TS which are operated from one extreme locked position to the other by means of switch machines 1SM and 2SM respectively.

Switch machine 1SM is operated by switch machine control relay 1SMR and switch machine 2SM is operated by switch machine control relay 2SMR. These control relays are of the two-position polar magnetic stick type and are governed from the control office through the medium of the communication system herein disclosed. Two control relays are illustrated for the purpose of indicating how two track switches may be controlled at a single step of the stepping bank. These switch control relays control the operation of the associated switch machines by energizing their normal or reverse operating wires from a local source of current, it being assumed that each switch machine is operated to its normal locked position when the polar contacts of the associated switch control relay are actuated to the right and when these contacts are actuated to the left the associated switch machine is operated to its reverse locked position. It will be understood that this control preferably includes suitable approach locking means and such other automatic signalling circuits as are usually employed in practice, but which are not shown in the present disclosure for the sake of simplicity.

Suitable signals (not shown) are associated with the illustrated track switches for governing traffic thereover and are provided with automatic signalling means interrelating traffic over the track switch with such other sections of track and traffic controlling devices as may be associated therewith. These signals are likewise governed from the control office through the medium of the communication system by signal control relays, not shown. Such signal control relays may be operated in a manner similar to the operation of the switch control relays, as later described.

For the purpose of illustrating how indications are transmitted by timing the "on" periods of a cycle and by superimposing alternating current on the line circuit during the "on" and "off" periods, code jumpers 210, 211, 212, and 213 are provided. For the purpose of illustrating how indications are transmitted from a registered station, track relay TR and signal repeating relay M are illustrated.

The communication part of the system includes polar line relay F¹ and its quick-acting repeating relay FP¹. Slow-acting relays SA¹ and SB¹ are for a purpose similar to that explained in connection with corresponding relays in the control office, these relays being picked up at the beginning of a cycle of operations, maintained picked up throughout the cycle and dropped out during the "clearing-out" period at the end of the cycle.

The field station includes a bank of stepping relays, comprising relays 1V¹, 2V¹, 3V¹, and VP¹ which correspond to similar relays in the control office. These relays are operated by circuits similar to the circuits for corresponding relays in the control office and in synchronism therewith, therefore it is believed unnecessary to illustrate the detailed circuits of the field station stepping relay bank.

For the purpose of illustrating the selection of a station for the transmission of controls, relay SO and relay SOS have been shown. A field change relay CH is shown to illustrate how a

cycle of operations is initiated from a field station.

For the purpose of illustrating the manner of determining when a field station is to transmit its indications, lock-out relay LO¹ is employed. When relay LO¹ is picked up during a cycle of operations to permit the field station to transmit, the impulses applied to the line circuit (in the control office) are left normally long or are made abnormally short by the field station relay PF¹. During the transmission of indications the picking up of relay LO¹ is also effective to permit the control of indication transmitting relays FZ¹ and BZ¹ in accordance with whether or not alternating current is to be allowed to flow over the line circuit to the control office or whether it is to be shunted away from the line circuit leading to the control office by a shunt provided at the transmitting field station. Relay PF¹ converts a normally long direct current impulse applied by the office to the control line circuit, to an abnormally short impulse in accordance with indications to be transmitted from a station marked by relay LO¹ being picked up.

Relays PT¹ and PB¹ control the continuity of the line circuit for purposes which will be described in detail. A filter, comprising inductances 2IN¹, 3IN¹ and condensers 2C¹ and 1C¹, is connected in the line circuit and is for the purpose of preventing or permitting the flow of alternating current over the line circuit to the office in accordance with whether the code being transmitted requires or does not require the transmission of alternating current. Certain resistances, inductances and condensers are also provided at the field station, the purpose of which will be pointed out in detail.

It is believed that the nature of the invention, its advantages and characteristic features will best be understood with further description being set forth from the standpoint of operation.

Operation

The system of the present invention is normally in a condition of rest, from which it may be initiated into a cycle of operations either from the control office or from any one of the field stations when there are new controls or new indications, respectively, ready to be transmitted. If new controls for several different field stations are ready for transmission at substantially the same time, they are transmitted on separate cycles, one station for each cycle. Similarly, if several field stations have indications ready for transmission at the same time, they are transmitted from such field stations to the control office, one station for each cycle.

It may happen that there are new controls and new indications ready to be transmitted at the same time and in such instances controls are transmitted to a selected field station simultaneously with the transmission of indications from the same or some other field station during the same cycle.

Irrespective of whether a cycle is to be for the transmission of controls and/or the transmission of indications, a predetermined number of impulses are placed upon the line circuit to accomplish the step-by-step operation of the stepping relay banks. These impulses are time-spaced, that is, they are separated by time spaces and the lengths of these time spaces are varied in accordance with the control code to be transmitted. During an indication cycle when no controls are being transmitted the time spaces

between impulses are all comparatively short. When a cycle is initiated for the transmission of controls the character of the impulses placed upon the line circuit is determined in accordance with the station to be selected and the controls to be transmitted. The lengths of the time spaces and the character of the impulses are determined by code jumpers for selecting the station and control levers for transmitting controls to the selected station.

During a cycle of operations initiated for the transmission of indications alone, the character of the impulses placed upon the line circuit and the lengths of the spaces between impulses are such that no station will be selected, these impulses merely causing the step-by-step operations of the control office stepping relay bank and the particular field station stepping relay bank which is transmitting. A series of impulses which selects no station for an out-bound call is referred to as a control phantom code. Such a code in the present embodiment comprises one or more (—) impulses and one or more normally short-time spaces, the number of which is determined by the number of station selection steps.

When a cycle of operations is initiated from a field station for the transmission of indications, a plurality of impulses are placed upon the line circuit in the control office to cause the step-by-step operations of the stepping relay banks and these impulses are made normally long or abnormally short to make up a portion of the code determined by the field station transmitting and in accordance with indications to be transmitted from the station which is transmitting. In addition to the length of the impulses, the indication code is further made up by the transmitting field station permitting or preventing alternating current flow over the line circuit to the control office. Alternating current is superimposed on the line circuit at the end station in one embodiment and at the transmitting station in the other embodiment.

Normal at rest conditions.—The two-wire line is normally energized over a circuit which may be traced from the (+) terminal of battery LB (Fig. 1A), back contact 20 of relay PC, front contact 21 of relay NC, conductor 22, inductance 1IN¹, return line conductor R, inductance 1IN¹, return conductor R¹, back contact 323 of relay LO², secondary winding of transformer TF², back contact 320 of relay PF², back contact 321 of relay PB², inductances 3IN² and 2IN² in series, winding of relay F², line conductor L, inductance 2IN, winding of relay F, conductor 158, back contact 30 of relay 1E, back contact 31 of relay 2E, back contact 32 of relay 4E, back contact 33 of relay LG, front contact 34 of relay NC and back contact 35 of relay PC to the (—) terminal of battery LB. The current flow in this direction will be conveniently referred to as (—) and it is effective to maintain relay F in its picked up position and relays F¹ and F² with their polar contacts positioned to the left. It will be understood that the polar contacts of line relays at other stations connected to the communication system will likewise have their polar contacts positioned to the left.

Relay NC is normally energized over a circuit extending from (+), back contact 36 of relay SD, back contact 31 of relay C, back contact 38

of relay CF, conductor 39, NC bus 40 and winding of relay NC to (—). Relay SC in the control office is normally energized over an obvious circuit completed at back contact 41 of relay SB.

At the station, relay PT¹ is normally energized over a circuit extending from (+), contact 222 of relay F¹ in its left hand position, back contact 223 of relay SB¹ and winding of relay PT¹ to (—). Relay CH at the field station is assumed to be normally energized over a circuit not shown and it will be assumed that this relay is de-energized when the associated field station has new indications to transmit. Track relay TR (Fig. 2A) is illustrated in its picked up position, it being assumed that the track section with 15 which it is associated is unoccupied. Relay M is shown picked up, it being assumed that all signals associated with the illustrated track section are at stop.

Manual start.—With the system in a condition of rest it may be manually initiated into a cycle for the transmission of controls. Whenever such a cycle is desired the operator first positions the control levers for the field station which he desires to select and then actuates the starting button associated with this station.

For the purpose of considering the operation of the present system it will be assumed that levers 1SML and 2SML are actuated to their normal positions (as indicated) for operating the associated track switches (Fig. 2B) to their normal locked positions and that starting button STB is actuated to start the cycle of operations. The actuation of button STB causes relay CD to be picked up and stuck up until the end of the cycle. The actuation of button STB also applies (+) to C bus 42, which causes current to flow over this bus, back contact 43 of relay OC, back contact 44 of relay SB and lower winding of relay C to (—). Relay C is picked up and closes a stick circuit for itself extending from (+), front contact 45 of relay SC, front contact 46 and upper winding of relay C to (—). The picking up of relay C prevents the energization of relay CF, after the start of this cycle, by opening back contact 47.

The picking up of relay C closes a circuit for picking up relay OC which extends from (+), back contact 36 of relay SD, front contact 37 of relay C and winding of relay OC to (—). The picking up of relay C de-energizes relay NC by opening the above described normal energizing circuit at back contact 37. The opening of back contact 43 of relay OC opens the above described pick-up circuit of relay C, so that the energization of this relay is held off at the end of the cycle for purposes which will be later described.

A circuit is now closed for picking up relay PC which extends from (+), front contact 48 of relay OC, front contact 49 of relay C, back contact 51 of relay 3V, back contact 52 of relay 2V, back contact 53 of relay 1V, PC bus 54 and winding of relay PC to (—). The dropping of relay NC and the picking up of relay PC changes the energization of the line circuit from (—) to (+) by means of pole-changing contacts 20, 21, 34, and 35 of these relays. This change in polarity of energization of the line circuit momentarily drops relay F, which is again immediately picked up and is ineffective. This re-energization of the line circuit reverses the positions of the polar contacts of the line relays at the stations from their left hand positions to their right hand dotted positions. Relay 3E

is picked up over a circuit which extends from (+), front contact 55 of relay OC, conductor 160, back contact 56 of relay 2E and winding of relay 3E to (-).

- 5 A circuit is now closed for picking up relay FP which extends from (+), front contact 57 of relay PC, conductor 58, front contact 59 of relay F and winding of relay FP to (-). A circuit is now closed for picking up relay SA which extends from (+) applied to conductor 58 over the above described circuit and extending through front contact 60 of relay FP to the winding of relay SA. A circuit is closed for picking up relay SB which extends from (+), front contact 61 of relay SA and winding of relay SB to (-). Relay SB opens the normally energized circuit for relay SC at back contact 41, which causes the de-energization of relay SC. Another stick circuit is closed for relay C at front contact 93 of relay SB, which is effective before relay SC drops and opens its front contact 45.

Relay SD is picked up over an obvious circuit closed at back contact 62 of relay SC. The closure of front contact 63 of relay SB applies energy to the plate circuits of the vacuum tubes and since this relay is maintained in its picked up position throughout the following cycle, the plate circuits are maintained energized during the cycle. The picking up of relay SD opens the pick-up circuit for relay CF at back contact 64 for the purpose of holding off the picking up of relay CF until all of the relays have been restored to normal at the end of the cycle. The opening of back contact 44 of relay SB also opens the above described pick-up circuit for relay C so that the pick-up operation of this relay is held off at the end of the cycle for a purpose which will be later described.

40 It will be understood that the intermittent energization of relay SA by contact 60 of relay FP, supplemented during a long "off" by contact 12 of relay 1E, are at such a rate that relay SA does not have time to drop out during an operating cycle. (+) energy is applied to conductor 58 at front contact 5 of relay SD to supplement that at contact 57 of relay PC, since contact 57 may not be closed during each "on" period.

45 *Stepping and impulsing operations.*—Relay VP is picked up over a circuit extending from (+), front contact 65 of relay SD, front contact 66 of relay FP, back contacts 67, 68 and 69 of relays 3V, 2V, and 1V respectively and winding of relay VP to (-). Relay VP closes a first stick circuit for itself which extends from (+), front contact 65 of relay SD, front contact 70 of relay VP and over the remainder of the above described circuit to the winding of relay VP.

50 Relay 1E is now picked up over a circuit extending from (+), front contact 65 of relay SD, back contacts 71, 72 and 73 of relays 3V, 2V, and 1V respectively, front contact 74 of relay VP, conductor 161, and winding of relay 1E to (-). Relay 2E is picked up over an obvious circuit closed at front contact 75 of relay 1E. The picking up of relay SD opens the above described pick-up circuit for relay OC, but before OC has time to release, a stick circuit is closed from (+), front contact 36 of relay SD, front contact 9 of relay OC, conductor 162, front contact 8 of relay 2E, conductor 163 and winding of relay OC to (-). Relay OC is held up throughout the cycle by

means of this stick circuit and the one in multiple with contact 8 completed at front contact 7 of relay 5E.

5 The picking up of relay 2E opens the above described energizing circuit for relay 3E at back contact 56, which drops relay 3E and a circuit is closed for picking up relay 4E which extends from (+), back contact 76 of relay 3E, back contact 77 of relay MF, conductor 133, front contact 78 of relay FP, conductor 164 and winding of relay 4E to (-). Relay 4E closes a stick circuit for itself which extends from (+), back contact 76 of relay 3E, front contact 79 and winding of relay 4E to (-). Relay 4E closes an obvious pick-up circuit for relay 5E at front contact 80.

10 The picking up of relay 4E opens the line circuit at back contact 32 which de-energizes the line and allows relay F to drop. The dropping of relay F causes the dropping of relay FP by opening front contact 59. The dropping of relay FP closes a second stick circuit for relay VP which extends from (+), front contact 65 of relay SD, back contact 66 of relay FP, front contact 81 and winding of relay VP to (-).

15 A circuit is now closed for picking up relay 1V which extends from (+), back contact 82 of relay FP, front contact 83 of relay SD, front contact 84 of relay VP, back contact 85 of relay 2V and winding of relay 1V to (-). Relay 1V closes a stick circuit for itself which extends from (+), front contact 86 of relay SD, front contact 87 and winding of relay 1V to (-). Since front contact 41 of relay SB is closed, 35 it will be obvious that the intermittent closing and opening of back contact 88 of relay FP causes the intermittent energization and de-energization of relay FPA, but since this operation of relay FPA has no function during a control 40 cycle, its operation at each step will not be pointed out.

20 The picking up of relay 1V opens the above described circuit of relay 1E at back contact 73, which allows relay 1E to drop, which in turn 45 de-energizes relay 2E at open front contact 75. Relay 3E is now picked up because of closed back contact 56 of relay 2E and relay 4E is dropped because of open back contact 76 of relay 3E. Relay 5E is dropped because of open 50 front contact 80 of relay 4E.

25 It will be assumed that the first impulse applied to the line circuit is (-) (for reasons later described), therefore relay NC will be assumed picked up so that the line circuit is energized 55 when relay 4E drops and closes its back contact 32 over a circuit including back contacts 31 and 30 of relays 2E and 1E respectively to the winding of relay F. This again picks up relays F and FP as previously described. Relay VP is now de-energized because its first stick circuit is open at back contact 69 of relay 1V and its second stick circuit is open at back contact 66 of relay FP. The dropping of relay VP completes the above described pick-up circuit for relay 1E, which now 60 extends through front contact 73 of relay 1V and back contact 74 of relay VP and the picking up of relay 1E effects the picking up of relay 2E, the dropping of relay 3E and the picking up of relays 4E and 5E in the manner previously described.

30 The picking up of relay 4E opens the line circuit at back contact 32 and the de-energization of the line effects the dropping of relays F and FP. A circuit is now closed for picking up relay 75

2V which extends from (+), back contact 82 of relay FP, front contact 83 of relay SD, back contact 84 of relay VP, back contact 89 of relay 3V, front contact 90 of relay 1V and winding of relay 5 2V to (-). Relay 2V closes an obvious stick circuit for itself at its front contact 91. The opening of back contact 72 of relay 2V de-energizes relay 1E, which in turn effects the dropping of relay 2E, the picking up of relay 3E and the dropping of relays 4E and 5E.

Relay 4E closes up the line circuit at its back contact 32 and it will be assumed that relay PC is in its picked up position for applying a (+) impulse to the line circuit at this time. The (+) 15 energy applied to the line circuit effects the picking up of relays F and FP and relay VP is now picked up over a circuit extending from (+), front contact 65 of relay SD, front contact 66 of relay FP, back contact 67 of relay 3V, front contact 20 68 of relay 2V and winding of relay VP to (-). Relay VP again closes its first stick circuit as previously described. Relay 1E is now energized because of closed front contact 72 of relay 2V and closed front contact 74 of relay VP 25 and relay 1E in turn effects the picking up of relay 2E, the dropping of relay 3E and the picking up of relays 4E and 5E in a manner previously described.

Relay 4E opens up the line circuit at back contact 32 and the de-energization of the line circuit effects the dropping of relays F and FP. The above described second stick circuit for relay VP is now completed and a pick-up circuit is completed for relay 3V which extends from (+), back contact 82 of relay FP, front contact 83 of relay SD, front contact 84 of relay VP, front contact 85 of relay 2V and winding of relay 3V to (-). Relay 3V closes an obvious stick circuit for itself at its front contact 92.

Relay 1E is now de-energized because of open back contact 71 and this relay effects in turn the de-energization of relay 2E, the energization of relay 3E and the de-energization of relays 4E and 5E. The dropping of relay 4E again energizes the line circuit by closing back contact 32 and it will be assumed that relay NC is picked up for making the next impulse (-). The energization of the line circuit effects the picking up of relays F and FP and the dropping of relay VP in a manner previously described. The dropping of relay VP closes the pick-up circuit for relay 1E at back contact 74, which is completed through front contact 71 of relay 3V. Relay 2E is now picked up, relay 3E is dropped and relays 4E and 5E are picked up in the manner previously described.

The picking up of relay 4E again de-energizes the line circuit, which effects the dropping of relays F and FP. Since there are no more stepping relays to be picked up, the energizing circuit for relay 1E is not interrupted and this relay remains in its picked up position for maintaining relay 2E picked up. Relay 3E is down and relays 4E and 5E are up and stay up for a comparatively long interval of time which effects the clearing 65 out of the system.

During this "clearing out" period, relay SA is dropped because front contact 60 of relay FP remains open for an extended period of time. The dropping of relay SA effects the dropping of relay 70 SB because of open front contact 61, the dropping of relay SB effects the picking up of relay SC because of closed back contact 41 and the picking up of relay SC effects the dropping of relay SD because of open back contact 62.

75 Relay C is de-energized during the "clear-

ing out" period because relay SB opens its front contact 93 before relay SC closes its front contact 45, which is effective to open the stick circuit for relay C for a period of time sufficient to drop out this relay. The dropping of relay SD opens the 5 energizing circuit for relay 1E at front contact 65, which allows relay 1E to release, after which relay 2E is released, relay 3E is picked up and relays 4E and 5E are dropped out in the manner previously described.

The dropping of relay SD de-energizes the stick circuits of the stepping relays at open front contact 86 which effects the dropping of these relays. The dropping of relay SD also opens the stick circuit of relay OC at front contact 36 15 which effects the dropping of relay OC. Relay 3E is de-energized by the opening of front contact 55 of relay OC. The dropping of relay SD completes the above described pick-up circuit for relay NC at back contact 36, so that relay NC is 20 picked up for applying (-) energy to the line circuit, which in turn picks up relay F and the system is placed in its normal condition.

Selection of control code.—The step-by-step and impulsion operations, effective in response to the initiation of the system from the control office, have been pointed out and it was assumed that these impulses applied to the line circuit were of certain polarities. It will now be explained how these polarities are determined and 30 also how the lengths of the time spaces between impulses are determined, all in accordance with the code to be transmitted.

When the system is initiated as above described, the normally energized line is changed 35 from a (-) to a (+) energization for conditioning the various circuits. It will be assumed that code jumpers 10 and 11 and the switch machine levers 1SML and 2SML of Fig. 1C are in the positions illustrated.

Jumper 11 connected as shown determines that the first "off" period (following the conditioning "on" period) will be comparatively long. This is effected by the picking up of relay LG when relay 1V is picked up in the first "off" period, over 45 a circuit extending from (+), front contact 48 of relay OC, front contact 49 of relay C, front contact 50 of relay VP, back contact 23 of relay 2V, front contact 24 of relay 1V, conductor 25, front contact 26 of relay CD, jumper 11, LG bus 50 27, winding of relay LG, and front contact 28 of relay 5E to (-). The dropping of relay 4E and the closure of its back contact 32 during the first "off" period is ineffective to energize the line circuit because of open back contact 33 of relay 55 LG. When relay 5E drops during the first "off" period the above described circuit for relay LG is opened at front contact 28, which allows relay LG to drop away, but since this relay is of the slow release type, a comparatively long interval 60 of time will be measured off before relay LG closes its back contact 33.

When back contact 33 is closed the line is energized to mark the end of the first "off" period but in this instance the first "off" period is rendered comparatively long. In the event that jumper 11 is in its alternate dotted line position, relay LG is not picked up and the line circuit is energized by the closure of back contact 32 when relay 4E drops, which renders the first "off" 70 period comparatively short.

The polarity of the first "on" impulse (following the first "off" period) is determined by the position of jumper 10. With jumper 10 in the position shown, relay NC is picked up during the 75

first "off" period, when relay **IV** picks up to de-energize the previously described circuit for relay PC at back contact **53**. The pick-up circuit for relay NC extends from (+), front contact **48** of relay OC, front contact **49** of relay C, back contacts **51** and **52** of relays **3V** and **2V** respectively, front contact **53** of relay **IV**, conductor **29**, front contact **19** of relay CD, jumper **10** and winding of relay NC to (-). With relay NC up and with relay PC down the pole-changing contacts **20**, **21**, **34** and **35** effect the application of a (-) impulse to the line circuit. In the event that jumper **10** is in its alternate dotted line position, then the above described circuit extends through the winding of relay PC instead of relay NC, which would pick up relay PC and prevent the picking up of relay NC, thus resulting in a (+) impulse being applied to the line circuit.

It will thus be seen that the code sending relays are positioned upon the picking up of the stepping relays during the "off" periods, while the line circuit is de-energized, in readiness for energizing the line with the selected polarity at the beginning of the next "on" period. Although it is assumed that the station is selected on a single step in the present embodiment, thus requiring only code jumpers **10** and **11**, it will be understood that in systems of larger capacity additional code jumpers will be provided and selected on one or more additional steps of the stepping relay bank. The above typical example illustrates how the station selecting code is applied to the line so that any one of four separate codes are selectively applied for a single step of the cycle. These codes are, first, long "off" and (-) "on", second, short "off" and (-) "on", third, long "off" and (+) "on" and fourth, short "off" and (+) "on".

The code which is selected during the second "off" period in the present embodiment is determined by the positions of levers **1SML** and **2SML**. With lever **1SML** in its normal position as illustrated, relay PC is picked up during the second "off" period (in order to make the second impulse (+)) over a circuit extending from (+), front contact **48** of relay OC, front contact **49** of relay C, back contact **51** of relay **3V**, front contact **52** of relay **2V**, conductor **18**, front contact **17** of relay CD, lever **1SML** in its normal position and winding of relay PC to (-). In the event that lever **1SML** is in its reverse dotted line position, then relay NC is picked up to apply a (-) impulse to the line circuit during the second "on" period.

With lever **2SML** in its normal position as illustrated, the second "off" period is rendered short because relay LG is not picked up during this "off" period, so that the line is energized to mark the beginning of the second "on" period when relay **4E** drops to close back contact **32**. In the event that lever **2SML** is in its reverse dotted line position, then relay LG is picked up over a circuit extending from (+), front contact **48** of relay OC, front contact **49** of relay C, back contact **50** of relay VP, back contact **16** of relay **3V**, front contact **15** of relay **2V**, conductor **14**, front contact **13** of relay CD, lever **2SML** in its reverse dotted line position, winding of relay LG and front contact **28** of relay **5E** to (-). In this case relay LG maintains the line circuit open for a comparatively long interval of time to provide a long "off" period between the first and second impulses in the same manner as previously explained in connection with the first "off" period.

From the above it will be seen that the impulses applied to the line circuit begin with a (+) im-

pulse for conditioning purposes when the cycle is initiated from the control office, with the following impulses being (+) or (-) and the time spaces between these impulses being long or short, dependent upon the code jumper and control lever connections as rendered effective by the particular code determining relay which is picked up for that cycle.

Station selection for controls.—It will be obvious that the impulses and the time spaces between impulses are received at all of the field stations, since the field station line relays are all included in the line circuit. However, for convenience in describing the operation of station selection, reference will be made to Figs. 2, 2A, and 2B which illustrate a typical field station somewhat in detail and which for convenience is considered to be the first station of the series and selected by the code applied to the line circuit as previously explained, which code is, first "off" long and first "on" (-). The illustrated field station is rendered responsive to this particular code because of the connections of jumpers **200**, **201**, and **202** as illustrated.

The conditioning (+) impulse applied to the line circuit actuates the polar contacts of relay **F¹** to the right. A circuit is now closed for picking up relays **SO** and **SOS** which extends from (+), back contact **203** of relay **SB¹**, contact **204** of relay **F¹** in its right hand dotted position, conductor **192**, back contact **205** of relay **L**, back contacts **206**, **207** and **208** of relays **3V¹**, **2V¹**, and **IV¹** respectively and the upper windings of relays **SO** and **SOS** in series to (-).

A circuit is now closed for picking up relay **FP¹**, which extends from (+), contact **222** of relay **F¹** in its right hand dotted position, back contact **224** of relay **LO¹**, conductor **193**, front contact **225** of relay **SO**, conductor **194** and winding of relay **FP¹** to (-). Relay **SA¹** is picked up over an obvious circuit closed at front contact **226** of relay **FP¹** and relay **SB¹** is picked up over an obvious circuit closed at front contact **227** of relay **SA¹**.

The picking up of relay **SB¹** closes a stick circuit for relay **SO** which extends from (+), front contact **203** of relay **SB¹**, conductor **195**, front contact **214** of relay **SOS**, front contact **215** and lower winding of relay **SO** to (-). A stick circuit is also closed for relay **SOS** which extends from (+), front contact **203** of relay **SB¹**, front contact **217** of relay **FP¹**, conductor **196**, front contact **216** and lower winding of relay **SOS** to (-). The picking up of relay **SO** applies (+) by way of its front contact **209** and conductor **181** to contact **204** of relay **F¹** to replace the (+) which is opened at back contact **203** of relay **SB¹**. This (+) at front contact **209** of relay **SO** is applied to the selecting circuit for this relay as will be later pointed out, so that the dropping of an SO relay during a cycle rules out the particular station with which this SO relay is associated, because the original pick-up circuits for the SO relays extend through back contacts of the SB relays, such as back contact **203**.

It will be understood that the intermittent energization of relay **SA¹** by contact **226** of relay **FP¹**, supplemented during a long "off" by contact **189** of relay **T**, are at such a rate that relay **SA¹** does not have time to drop out during an operating cycle. It will also be understood that the first impulse (conditioning "on" impulse) is somewhat longer than the remaining impulses of the cycle so that relays **SA¹** and **SB¹** have time to pick up during the time that the line circuit is energized. It will further be understood that

similar circuits are established at all other field stations for picking up the associated SO and SOS relays and that the same operations take place at these other stations during the conditioning "on" period. The SO relays are dropped at these other stations during the station selection portion of the code and maintained picked up at the illustrated station in response to the assumed station selecting code.

At the illustrated station, relay FP¹ repeats the operations of relay F¹ over the above described pick-up circuit, including front contact 225 of relay SO, when contact 222 of relay F¹ is in its right hand dotted position. When contact 222 is in its left hand position the energizing circuit for relay FP¹ extends through front contact 223 of relay SB¹. During the conditioning "on" period, relay VP¹ is picked up over a circuit which is not shown but which is similar to the pick-up circuit for relay VP in the control office.

Relay T is picked up during the conditioning "on" period over a circuit which extends from (+), front contact 218 of relay SB¹, front contact 219 of relay FP¹, conductor 197 and winding of relay T to (-). Relay T is somewhat slow in picking up so that a circuit is effective for picking up relay L before relay T picks up, which circuit extends from (+), front contact 218 of relay SB¹, conductor 198, back contact 228 of relay T and winding of relay L to (-). Relay L closes a stick circuit for itself which extends from (+), front contact 218 of relay SB¹, front contact 229 of relay FP¹, conductor 199, front contact 230 and winding of relay L to (-).

When the line circuit is deenergized to mark the end of the conditioning "on" period and the beginning of the first "off" period, the polar contacts of relay F¹ (and of course the polar contacts of the line relays at all other stations) are restored to their neutral positions. The opening of contact 222 of relay F¹ drops relay FP¹ which is effective to pick up relay F¹ over a circuit which is not shown but which is similar to the corresponding circuit in the control office.

Relay SO is stuck up during the first "off" period by means of a circuit closed at back contact 217 of relay FP¹, which circuit extends from (+), front contact 203 of relay SB¹, back contact 217 of relay FP¹, conductor 180, front contact 215 and lower winding of relay SO to (-). Relay SOS is deenergized when relay FP¹ is dropped during the first "off" period because of open front contact 217 of relay FP¹ and because of open contact 204 of relay F¹.

The dropping of relay FP¹ during the first "off" period effects the dropping of relay L because of open front contact 229 of relay FP¹, since back contact 228 of relay T is also open. The opening of front contact 219 of relay FP¹ deenergizes relay T, but since this relay is slow releasing it will maintain its contacts picked up for a comparatively long interval of time. Since the first "off" period is long and since the drop-away time of relay T is less than the length of a long "off" period, relay T will drop away before the line circuit is energized to mark the end of the first "off" period and the beginning of the first "on" period. The dropping of relay T closes a circuit at back contact 228 for again picking up relay L.

At the end of the first "off" period and the beginning of the first "on" period the (-) energization of the line circuit causes relay F¹ to actuate its polar contacts to the left, which in

turn picks up relay FP¹. The picking up of relay FP¹ closes the above described stick circuit for relay L at front contact 229 so that this relay is maintained picked up throughout the first "on" period. The picking up of relay FP¹ again closes the pick-up circuit for relay T at front contact 219 and relay T opens the pick-up circuit of relay L at back contact 228, but because of the fact that relay L was picked up during the first long "off" period it is maintained stuck up throughout the next (first) "on" period. It will be apparent that a short "off" period would not permit the dropping of relay T because the drop-away time of this relay is longer than a short "off" period. When relay T is not permitted to drop during an "off" period (short), then after relay L is dropped by the opening of front contact 229 of relay FP¹, it cannot be again picked up during this "off" period so that it is maintained in its dropped away position throughout the next "on" period.

From the above it will be observed that relay T detects the length of an "off" period by dropping during a long "off" and remaining picked up during a short "off", and that relay L stores this detected condition throughout the succeeding "on" period by remaining picked up throughout the succeeding "on" in response to a preceding long "off" and remaining down throughout the succeeding "on" in response to a preceding short "off".

The first selection in response to the station selection code is made during the first "on" period when relay FP¹ is picked up. In the example assumed the long "off" and (-) "on" code closes a selecting stick circuit for relay SO which extends from (+), front contact 209 of relay SO, conductor 181, contact 204 of relay F¹ in its left hand position, conductor 182, front contact 231 of relay L, back contacts 232 and 233 of relays 3V¹ and 2V¹ respectively, front contact 234 of relay F¹, code jumper 202 in its full line position and upper windings of relays SO and SOS to (-). It will be observed that jumper 202 in its dotted line position would render the above described selecting stick circuit for relay SO incomplete so that this relay would be dropped out when relay FP¹ opened its back contact 217. With the selecting stick circuit complete however, relay SO is maintained energized and relay SOS is picked up and the stick circuit for relay SOS is again completed by way of front contact 217 of relay FP¹. The picking up of relay SOS likewise again completes the stick circuit for relay SO by way of front contacts 214 and 215.

From the above it will be observed that a first code comprising a short "off" and a (+) "on" will be ineffective to maintain relay SO energized during the selecting period because of jumper 200 not connecting to the SO relay circuit. Likewise a first code comprising a long "off" and a (+) "on" will not energize relay SO because of jumper 201 being in its open circuit position. It will thus be apparent that relay SO at the station to be selected is maintained energized by a composite code made up of the polarity of the first impulse and the length of the time space preceding this impulse as repeated by relays F¹ and L.

With the provision of two separate code jumpers in the office as illustrated, four different code combinations are possible on the first step of the cycle, three of which may be employed for station selection, with the fourth being used for the phantom control code call. It is obvious that the sys-

tem will transmit a normally short "off" and a (—) "on" at the first step if no CD relay in the office is picked up as a result of the system being initiated from a field station. No station must be selected in response to this code and therefore front contact 235 of relay 1V¹ is not connected to a code jumper, since this contact is the one selected by the phantom code when a single station selection code selecting step is provided. It will be obvious that, in the event of two station selecting steps, this front contact 235 will lead to a jumper and the front contacts illustrated in connection with the four code circuits of relay 2V¹ will be used to provide a total of 15 station selection codes, that is 4×4 minus 1, the sixteenth being the phantom code.

In the above example it will be obvious that three stations may be selected on a single step of the system and that the second station will be responsive to a long "off" and a (+) "on" code. At this station the jumper corresponding to jumper 201 of Fig. 2A will be connected in its lower position and the other two jumpers will be in their upper positions. The third station will be responsive to a short "off" and a (+) "on" code and at this station the jumper corresponding to 200 will be in its lower position and the other two jumpers will be in their upper positions.

It will be obvious that the long "off" and (+) "on" station selecting code will be determined in the office by two jumpers selected by the associated CD relay similar to jumpers 10 and 11 of Fig. 1C, with the jumper similar to jumper 10 being connected to the PC bus and with the jumper similar to jumper 11 being connected to the LG bus. Likewise the short "off" and (+) "on" code will be provided in the control office by having the jumper for this station, similar to jumper 10, being connected to the PC bus and the jumper similar to jumper 11 being disconnected from the LG bus.

The succeeding impulses of the cycle will be effective to govern the control relays of the selected station only. Upon the picking up of relay 2V¹ at the selected station in response to the second "off" period, a stick circuit is provided for relay SO which is maintained complete throughout the remainder of the cycle. This is conveniently referred to as the permanent stick circuit and extends from (+), front contact 203 of relay SB¹, conductor 195, front contact 236 of relay 2V¹, front contact 215 and lower winding of relay SO to (—). Relay SOS is dropped out during the second "off" period when relay FP¹ is released, because of its open front contact 217 and because there is no circuit including the upper windings of the SO and SOS relays energized after relay 2V¹ is picked up. Relay SOS therefore remains deenergized throughout the remainder of the cycle.

Transmission of controls.—It will be recalled that the second "off" period was normally short because lever 2SML in its normal position was not effective to pick up relay LG during this "off" period and also that the second "on" period was (+) because lever 1SML in its normal position effected the picking up of relay PC. The (+) impulse is received at the illustrated station by line relay F¹ positioning its polar contacts to the right. This closes a circuit for energizing switch machine control relay 1SMR which extends from (+), front contact 209 of relay SO, conductor 181, contact 204 of relay F¹ in its right hand dotted position, conductor 192, back contact 237 of relay 3V¹, front contact 238 of relay 2V¹, conductor 239

and upper winding of relay 1SMR to (—). Current through the upper winding of this relay positions its polar contact to the right for energizing the normal circuit of switch machine 1SM for controlling the position of track switch 1TS to its normal position. In the event that lever 1SML is in its reverse dotted line position, then the second impulse will be (—) and relay F¹ will close a circuit at contact 204 in its left hand position, conductor 182, back contact 240 of relay 3V¹, front contact 241 of relay 2V¹, conductor 242 and lower winding of relay 1SMR to (—). Current through this winding of switch machine control relay 1SMR positions its polar contact to the left for causing the switch machine to actuate the associated track switch to its reverse position.

The second normally short "off" period is terminated and relay FP¹ is picked up to reenergize relay T before its release, so that relay L remains down throughout the second "on" period in response to this normally short preceding "off" period. A circuit is closed for actuating the polar contact of relay 2SMR to its right hand position which extends from (+), front contact 243 of relay FP¹, conductor 183, back contact 244 of relay L, back contact 245 of relay 3V¹, front contact 246 of relay 2V¹, conductor 247 and lower winding of relay 2SMR to (—). In the event that lever 2SML is in its reverse position, then relay LG will be picked up to render the second "off" period abnormally long, so that relay L will remain picked up throughout the succeeding "on" period (in a manner described in connection with the first "on" period), to complete a circuit for actuating the polar contact of relay 2SMR to its left hand dotted position, which circuit extends from (+), front contact 243 of relay FP¹, conductor 183, front contact 244 of relay L, back contact 248 of relay 3V¹, front contact 249 of relay 2V¹, conductor 250 and upper winding of relay 2SMR to (—). The polar contact of relay 2SMR in its right hand position causes switch machine 2SM to position track switch 2TS to its normal position and with this contact in its left hand dotted position switch machine 2SM positions track switch 2TS to its reverse position.

In a similar manner additional steps may be used for transmitting additional controls to the illustrated field station for governing signals, but since the above typical examples illustrate the manner of such transmission it is believed unnecessary to illustrate the signal control relays which may obviously be controlled by the following polar impulses and time space lengths. Although the four code control circuits used for selecting the station in the manner previously described are shown connected through contacts of the 3V¹ and 2V¹ relays, it will be understood that where station selection is effected on the first step of the cycle these circuits need not connect through contacts of relay 3V¹, it only being necessary that they be broken by back contacts of relay 2V¹. The contacts associated with these circuits on the 2V¹ and 3V¹ relays are shown only for the purpose of indicating that they may be used for station selection in a system where such selection requires more than one step of the cycle and in this event of course the control circuits for controlling the switch control relays, and the like just described, will be transferred to additional stepping relays of the bank.

Following the application of the last impulse the line circuit is deenergized for a comparatively long interval of time referred to as the "clearing out" period. During this "clearing out" period

relay FP¹ remains down sufficiently long to effect the dropping of relays SA¹ and SB¹ in sequence, because of open front contacts 226 and 227 of relays FP¹ and SA¹ respectively. Relay T is dropped out during this "clearing out" period because of open front contact 219 of relay FP¹. The closure of back contact 228 of relay T will effect the picking up of relay L because of closed front contact 218 of relay SB¹, but relay L will be released when relay SB¹ releases and opens front contact 218. This operation of relay L is of no consequence.

The stepping relays at the field station are dropped out in the same manner as explained in connection with those at the control office, except that their stick circuits are controlled by relay SB¹. Relay SO is deenergized during the "clearing out" period when its permanent stick circuit is deenergized at open front contact 203 of relay SB¹. When the line circuit is reenergized at the end of the "clearing out" period, relay F¹ again positions its polar contacts to the left and the system is thereby placed in its normal condition.

During the operation of the control cycle above described, relay PT¹ is dropped out during the conditioning "on" period because of open back contact 223 of relay SB¹, but the release of relay PT¹ serves no purpose during a control cycle. Its function will be explained in connection with an indication cycle. Following the "clearing out" period, when the line circuit is reenergized, relay PT¹ is picked up over the circuit including contact 222 of relay F¹ in its left hand position. The system is now in its normal condition from which it may be again initiated.

Transmission of indications.—Although this system is of the coded duplex type and indications may be transmitted from any station to the control office during the same cycle that controls are transmitted to the same or some other station, it is convenient to first explain the communication of indications alone on a separate operating cycle, before considering the duplex feature of the system.

The manner in which field stations are allowed to transmit only one at a time in a pre-determined order will be explained in connection with the lock-out feature, this feature being included in the description following the description of the operation of the system with respect to the transmission of indications from a single field station, assuming that such field station is the only one having new indications to transmit at the beginning of the cycle.

Automatic start.—A change in the condition of the detector track section or a change in condition of other traffic controlling devices at the illustrated station may occur for effecting the initiation of the system for the transmission of indications. Although the detailed circuits are not shown, it will be assumed (and readily understood) that any such change may so condition these circuits that relay CH is dropped. The dropping of relay CH closes a circuit for picking up relay PB¹ which extends from (+), back contact 203 of relay SB¹, contact 204 of relay F¹ in its left hand position, conductor 182, back contact 231 of relay L, back contacts 251, 252 and 235 of relays 3V¹, 2V¹ and 1V¹ respectively, back contact 253 of relay CH, conductor 184, back contacts 254 and 255 of relays LO¹ and FP¹ respectively, front contact 256 of relay PT¹ and winding of relay PB¹ to (-). Relay PB¹ closes a stick circuit for itself which extends from (+),

front contact 257 of relay PT¹, front contact 258 and winding of relay PB¹ to (-).

The picking up of relay PB¹ opens the normally energized line circuit at open back contact 221, which effects the dropping of relay F¹. Relay PT¹ is deenergized because of open contact 222 and relay PT¹ drops after a comparatively long interval of time due to its slow-acting characteristics.

The opening of the line circuit also effects the dropping of relay F in the control office, which closes a circuit for picking up relay CF extending from (+), back contact 94 of relay 5E, conductor 151, back contact 95 of relay F, back contacts 64 and 47 of relays SD and C respectively and lower winding of relay CF to (-). Relay CF closes a stick circuit for itself extending from (+), front contact 45 of relay SC, front contact 96 and upper winding of relay CF to (-), and since relay SB picks up and closes its front contact 93 before relay SC drops and opens its front contact 45, this stick circuit is maintained throughout the cycle but is deenergized during the "clearing out" period for dropping out relay CF in the same manner that relay C was dropped as explained in connection with a control cycle.

Relay OC is now picked up over a circuit extending from (+), back contact 36 of relay SD, back contact 37 of relay C, front contact 38 of relay CF and winding of relay OC to (-). Relay OC remains up throughout this cycle and is dropped during the "clearing out" period in the same manner described in connection with a control cycle. The opening of back contact 38 of relay CF deenergizes relay NC and relay PC is picked up over a circuit extending from (+), front contact 48 of relay OC, back contact 49 of relay C, front contact 97 of relay CF, back contact 98 of relay 1V, PC bus 54 and winding of relay PC to (-). The dropping of relay NC and the picking up of relay PC energizes the line circuit with (+) energy, which is effective to pick up relays F and FP in the control office in a manner already described in connection with a control cycle.

The E relays and the slow-acting relays in the control office are now operated during the conditioning "on" period in the same manner as described in connection with a control cycle, following which the line is impaled and the stepping relays at the office and at the transmitting field station are operated in synchronism. During this cycle all of the impulses will be (-) following the conditioning (+) impulse, because NC bus 48 will be permanently energized when relay 1V picks up and closes its front contact 98. The time spaces between impulses will be normally short because no CD relay is picked up to complete an energizing circuit for relay LG. This series of (-) impulses and normally short time spaces comprises the phantom control code previously mentioned which is ineffective to select any station for controls.

Referring again to the field station, the (+) energization of the line circuit during the conditioning "on" period causes relay F¹ to position its polar contacts to the right. Relays SO and SOS are picked up but are dropped out in response to the phantom control code. A circuit is now closed for picking up relay LO¹ which extends from (+), back contact 203 of relay SB¹, contact 204 of relay F¹ in its right hand dotted position, conductor 192, back contact 205 of relay L, back contacts 206, 207, and 259 of relays 3V¹, 2V¹ and 1V¹ respectively, conductor 185, front

contact 260 of relay PB¹ and winding of relay LO¹ to (-). Relays FP¹ and SA¹ are picked up in the manner previously described, but relay SB¹ is not energized at this time due to open back contact 261 of relay PB¹. The picking up of relay LO¹ energizes the stick circuit of relay PB¹ over a circuit extending through back contact 262 of relay SA¹ and front contact 263 of relay LO¹, which circuit is deenergized when relay SA¹ picks up because relay PT¹ will be down at this time, therefore relay PB¹ is deenergized and after a comparatively long interval of time it is released.

The picking up of relay SA¹ closes a stick circuit for relay LO¹ extending from (+), front contact 264 of relay SA¹, front contact 265 and winding of relay LO¹ to (-), which stick circuit is maintained energized for holding relay LO¹ picked up until the "clearing out" period at the end of the cycle, when relay LO¹ is released by relay SA¹ opening front contact 264. When relay PB¹ drops and closes its back contact 261 the energizing circuit for relay SB¹ is completed and this relay picks up and remains up until the "clearing out" period at the end of the cycle.

Relay PT¹ remains down throughout the cycle and is again energized during the "clearing out" period. Relays T, L, FP¹ and the stepping relays are operated as in a control cycle, but the stepping relay bank at the transmitting station only is operated, because front contact 266 of relay SO and front contact 267 of relay LO¹ will both be open at other stations, so that the stepping relay circuit extending from (+) at a front contact similar to contact 268 of relay SB¹ and back contacts similar to contact 269 of relay FP¹ will be ineffective at stations not selected for controls or for the transmission of indications during the cycle.

40 The stepping relay bank at the transmitting station is operated however because of closed front contact 267 of relay LO¹ and it will be understood that, in the event of a duplex cycle where some other station is selected for controls, its SO relay will be picked up so that a contact similar to 266 will be closed for permitting operation of the stepping relay bank at that station.

Registration of a field station.—At the particular station having indications to transmit, lock-out relay LO¹ is up and, because of its open back contact 293, the transmitting contacts 276 and 285 of the FZ¹ and BZ¹ relays are rendered effective. Similarly, by the closure of its front contacts 270 and 271 of relay LO¹ the control circuits for the transmitting relays PF¹, FZ¹ and BZ¹ are rendered effective.

It will be understood that relay SA² at the end station (see Fig. 2B) is picked up during the conditioning "on" period so that the converter is started by the closure of front contact 322. This effects the application of alternating current to the line circuit by way of transformer TF² and this current finds a low impedance path from the right hand terminal of the secondary winding of transformer TF², by way of back contact 323 of relay LO² to line conductor R¹. From the left hand terminal of this transformer winding a low impedance path is provided by way of back contacts 320 and 321 of relays PF² and PB² respectively and the band pass filter, including inductances 3IN² and 2IN² and condensers 1C² and 2C², to conductor L¹. This alternating current finds a low impedance path through any other stations which may be located between the end station

and the transmitting station, similar to that just pointed out at the end station, so that a substantial alternating current potential appears on conductors R¹ and L¹ of Fig. 2.

It will be assumed that the transmitting station identifies itself in the control office by a code comprising "no alternating current" during the conditioning "on" period, "no alternating" current during the first "off" period, "alternating current" during the first "on" period and a short first "on" period. This code combination positions the polar contacts of relays 1PT to 4PT inclusive of Fig. 1C to the positions illustrated. These contacts in their illustrated positions may effect the picking up of a station relay to identify the transmitting field station, but in the drawings this station relay is not shown. However, a succeeding code circuit is illustrated as being connected through the polar contacts of these pilot relays in their illustrated positions to indication receiving relay 1IR, since this provides means for illustrating how an indication is transmitted and selectively received in the control office in accordance with the positions assumed by the pilot relays. The station identifying code is provided at the transmitting field station by jumpers 210 to 213 inclusive illustrated in Fig. 2A. It will now be explained how the code combination is provided by the particular jumper arrangement illustrated, and it will also be pointed out how alternate positions of each of these code jumpers select the alternate code for providing a choice of two code combinations for each jumper shown. It will be understood that, in systems of larger size, additional code jumpers will be provided and selected at additional steps of the cycle.

Code jumper 211 connected as illustrated in Fig. 2A determines that no alternating current shall be permitted to flow over the line circuit to the control office during the conditioning "on" period. This is brought about by picking up relay FZ¹ during the conditioning "on" period over a circuit extending from (+), jumper 211, back contact 272 of relay 1V¹, conductor 186, winding of relay FZ¹ and front contact 271 of relay LO¹ to (-). This pick-up circuit for relay FZ¹ is completed as soon as relay LO¹ is picked up during the conditioning "on" period and upon the picking up of relay FP¹ during this same period a stick circuit is completed for relay FZ¹ which extends from (+), front contact 273 of relay FZ¹, front contact 274 of relay FP¹, winding of relay FZ¹ and front contact 271 of relay LO¹ to (-). During the first "off" period, the dropping of relay FP¹ opens the stick circuit for relay FZ¹ and the picking up of relay 1V¹ opens the pick-up circuit of relay FZ¹ at back contact 272, thus effecting the release of relay FZ¹.

The alternating current connected to conductors L¹ and R¹ of Fig. 2, as previously explained, is by-passed or shunted at the transmitting field station during the conditioning "on" period in accordance with code jumper 211 in its illustrated position. This shunt circuit extends from conductor R¹, front contact 275 of relay FP¹, front contact 276 of relay FZ¹, inductance 3IN³, condenser 3C¹ and resistance 4R¹ to conductor L¹. It will be understood that this is a series resonant shunt circuit offering a minimum impedance to the frequency of the alternating current applied to the line circuit at the end station. Furthermore, a parallel resonant circuit is provided by inductance 1IN⁴ and condenser 1C¹ which traps or blocks out any of the alternating current not shunted by the above described shunt circuit.

In the event that jumper 211 is in its alternate dotted line position, then relay FZ¹ is not picked up during the conditioning "on" period and the above described shunt circuit is incomplete because front contact 275 of relay FP¹ leads through back contact 276 of relay FZ¹, which provides a circuit for the alternating current around the above mentioned parallel resonant circuit to conductor R. The alternating current is received in the control office as will be later described and finds a return path by way of line conductor L and through the filter to line conductor L¹. The above examples illustrate the choice of two code elements supplied by preventing or permitting alternating current to flow to the control office during the conditioning "on" period.

Code jumper 213 connected as shown in Fig. 2A, prevents alternating current flowing to the control office during the first "off" period because relay BZ¹ is picked up during the conditioning "on" period over a circuit extending from (+), jumper 213, back contacts 277, 278, and 279 of relays 1V¹, 2V¹, and 3V¹ respectively, conductor 187, front contact 280 of relay FP¹, winding of relay BZ¹ and front contact 271 of relay LO¹ to (-). When relay FP¹ is dropped during the first "off" period the circuit of relay BZ¹ is transferred from its pick-up to its stick circuit, which extends through back contact 280 of relay FP¹ and front contact 281 of relay BZ¹ to (+). Since this stick circuit remains effective throughout the first "off" period, relay BZ¹ is maintained stuck up until after the beginning of the first "on" period, when relay FP¹ is picked up to open the above described stick circuit.

With relay BZ¹ picked up throughout the first "off" period, the dropping of relay FP¹ at the beginning of this "off" period maintains the above described shunt for the alternating current by extending this shunt through back contact 275 of relay FP¹ and front contact 285 of relay BZ¹. In the event that jumper 213 is in its alternate dotted line position, then relay BZ¹ is not picked up during the conditioning "on" period and when relay FP¹ switches its contact 275 from its front to its back point at the beginning of the first "off" period, the above described shunt circuit is open at front contact 285 of relay BZ¹ and the alternating current is extended to conductor R by way of back contact 285.

The above examples illustrate how the choice of preventing or permitting alternating current to flow through to the control office is effected during the first "off" period. It is believed that these examples are sufficient to illustrate how these selections are made at other steps of the cycle so that it will be unnecessary to point out the detailed circuits for effecting this selection at other steps. It will only be mentioned that relay FZ¹ is conditioned during the first "off" period in accordance with the position of jumper 212 for preventing or permitting alternating current to flow through to the control office during the first "on" period. In other words, with jumper 212 in the position illustrated relay FZ¹ will not be picked up during the first "off" period, therefore it will not be up throughout the first "on" period and when relay FP¹ is picked up during the first "on" period, alternating current will flow by way of front contact 275 of relay FP¹ and back contact 276 of relay FZ¹ to line conductor R, returning over the previously described path. With jumper 212 in its alternate dotted line position, then it will be obvious from the previous example how alternating current is shunted away

from the line circuit leading to the control office during the first "on" period.

With code jumper 210 in the position illustrated in Fig. 2A, the first "on" period is made abnormally short because relay PF¹ is picked up during the first "on" period over a circuit extending from (+), jumper 210, front contact 282 of relay 1V¹, back contact 283 of relay 2V¹, back contact 284 of relay VP¹, conductor 188, front contact 270 of relay LO¹, front contact 286 of relay FP¹ and winding of relay PF¹ to (-). The picking up of relay PF¹ opens the line circuit by opening its back contact 220 before this line circuit is normally opened by the picking up of relay 4E in the control office.

Relays F¹ and FP¹ drop in response to the opening of the line circuit and relay PF¹ is deenergized at open front contact 286 of relay FP¹. In the event that jumper 210 is in its alternate dotted line position, then relay PF¹ is not picked up and the first "on" period is normally long as determined by the time of picking up relay 4E in the control office to terminate this "on" period. The above illustrates the selection of a choice of two code conditions for the first "on" period and it is obvious how other "on" periods may be selectively conditioned at additional steps of the cycle, from the above typical examples.

Referring to the control office, it will be recalled that energy is applied to the plate circuits of the vacuum tubes during the conditioning "on" period by the closure of front contact 63 of relay SB. Since the conditioning "on" code selected by code jumper 211 at the field station results in no alternating current getting through to the control office during the conditioning "on" period, relay MFZ which responds to this code is not picked up during the conditioning "on" period and this condition is executed during the first "off" period, during the interval between the dropping of relay F and the dropping of relay 2E, over a circuit extending from (B+), back contact 109 of relay MFZ, front contact 101 of relay 2E, conductor 152, back contact 102 of relay F, front contact 103 of relay SA, front contact 104 of relay CF, front contact 105 of relay VP, back contact 106 of relay 2V, conductor 107 and winding of relay 1PT to (CN). Current flowing over this circuit positions polar contact 108 of relay 1PT to the right.

In the event that alternating current is permitted to flow to the control office during the conditioning "on" period, this current will find a path of minimum impedance from conductor R, through resistance 3R, primary winding of in-put transformer 1IT and condenser 3C to conductor L. In response to this current flow an alternating potential is established across the in-put of tube 1VT, which causes a pulsating current to flow in the out-put circuit of this tube, including the primary winding of in-put transformer 2IT, which has its secondary winding connected to the in-put of tube 2VT, thus resulting in a pulsating current flowing through the primary winding of out-put transformer 1OT. This establishes an alternating potential across the terminals of the secondary of transformer 1OT which, by reason of its center tap and rectifiers 1RC and 2RC connected to the end terminals of this winding, causes uni-directional current to flow over a circuit extending from the center tap of this transformer winding, conductor 153, lower winding of relay MFZ, back contact 109 of relay FPA, back contact 110 of relay 2E, conductor 154, front contact 111 of relay FP, back

5 contact 112 of relay SC and front contact 113 of relay CF to the common connection of the two rectifiers. By means of this circuit each half-wave of the alternating current is passed through relay MFZ in the same direction and controls the

10 operation of relay MFZ.
 In the event that alternating current is received during the conditioning "on" period for picking up relay MFZ, this relay will be stuck up over a circuit extending from (+), back contact 114 of relay SC, conductor 155, front contact 115 of relay 1E, front contact 116 and upper winding of relay MFZ to (-). Since relay F drops during the first "off" period before relay 1E drops, 15 this stick circuit is also completed at back contact 117 of relay F, so that relay MFZ when up, remains stuck up throughout the "off" period until relay F picks up to open back contact 117. With relay MFZ stuck up through the first "off" 20 period, the above described executing circuit extends from (B-) at front contact 100 of relay MFZ for positioning polar contact 108 of relay 1PT to the left. This illustrates how the choice of two conditions of A. C. or no A. C. received in the control office during the conditioning "on" period selectively positions the polar contact of relay 1PT to either one of two positions.

25 Relay MBZ registers the "off" code element, that is whether alternating current is prevented from flowing or permitted to flow through to the control office during the "off" period. With jumper 213 at the field station in the position illustrated, no alternating current flows through 30 to the control office during the first "off" period and relay MBZ is not picked up. During the first "on" period this condition is executed while relay F is picked up, over a circuit extending from (B+), back contact 118 of relay MBZ, conductor 155, front contact 119 of relay F, front contact 120 of relay CF, back contacts 121 and 122 of relays 3V and 2V respectively, front contact 123 of relay 1V, conductor 124 and winding of relay 2PT to (CN). Current flow in this direction over this circuit positions polar contact 45 99 of relay 2PT to the right.

35 In the event that alternating current is permitted to flow through to the control office, because jumper 213 is in its alternate dotted line position, this current is detected by the vacuum tubes as previously described and causes uni-directional current to be applied over a circuit extending from the mid-tap of transformer 1OT, conductor 153, lower winding of relay MBZ, front contact 125 of relay 4E, back contact 126 of relay 1E, conductor 156, back contact 111 of relay FP, back contact 112 of relay SC, front contact 113 of relay CF and through the rectifiers to the terminals of the transformer winding. This 40 picks up relay MBZ which closes a stick circuit for itself extending from (+), back contact 114 of relay SC, conductor 155, front contact 127 of relay 3E, front contact 128 and upper winding of relay MBZ, to (-). Since relay F is picked up at the beginning of the first "on" period before relay 3E is dropped during this period, the stick circuit for relay MBZ is also completed at front contact 117 of relay F, thus maintaining relay MBZ stuck up, when once picked up, through 45 out the "on" period following the "off" period during which it was picked up. With relay MBZ picked up the above described executing circuit extends from (B-) at front contact 118 of this relay for positioning polar contact 99 of relay 50 2PT to the left. The above examples illustrate

5 how the choice of two conditions (A. C. or no A. C. received during an "off" period) are registered and executed in the control office.

10 In response to the first "on" period being made abnormally short (because of jumper 210 in its illustrated position) relay MF in the control office is picked up because relay F drops before relay 4E picks up to open the line. The pick-up circuit for relay MF extends from (+), back contact 129 of relay SC, back contact 130 of relay F, conductor 135, back contacts 131 and 132 of relays 4E and 5E respectively, back contact 134 of relay LG and winding of relay MF to (-). Relay MF closes a stick circuit for itself which extends from (+), back contacts 129 and 130 of relays SC and F respectively, conductor 135, back contact 136 of relay 3E, front contact 137 and winding of relay MF to (-). With relay MF picked up in the first "on" period the above described stick circuit maintains it energized throughout the following (second) "off" period, until the beginning of the second "on" period when it is deenergized by relay F opening its back contact 130.

15 This condition is executed during the second "off" period by applying (B+) to pilot relay 3PT over a circuit extending from (B+), front contact 138 of relay MF, front contact 139 of relay 4E, back contact 140 of relay 3E, conductor 157, front contact 141 of relay SA, front contact 142 of relay CF, back contact 143 of relay VP, back contact 144 of relay 3V, front contact 145 of relay 1V, conductor 146 and winding of relay 3PT to (CN). Current flowing over this circuit in this direction positions polar contact 146 of relay 3PT to the right. In the event that jumper 210 is in its alternate dotted line position for leaving the first "on" period normally long, then relay MF will not be picked up and the above executing circuit will extend from (B-) at back contact 138 of relay MF for positioning polar contact 146 of relay 3PT to the left. The above examples illustrate how the choice of a short or a long "on" period is registered in the control office and executed to selectively position a pilot relay in one or the other of two positions.

20 Since it was assumed that the station registration code permitted alternating current to flow through to the control office during the first "on" period (because of the position of jumper 212 at the station) it will be obvious from the above description that relay 4PT will position its polar contact 147 to the left in response to this code. This may be understood by analogy to the above example, where it was explained how relay 1PT positions its polar contact to the left in response to the flow of alternating current during the conditioning "on" period.

25 With contacts 108, 99, 146, and 147 of relays 1PT to 4PT inclusive respectively in the positions illustrated, the illustrated station is identified in the control office by completing a circuit through these contacts in these positions for registering the indications transmitted from this station. It will be obvious that other transmitting stations will position these four pilot relays in other combinations of positions for identifying other stations in a manner which will be obvious from the above example.

30 *Transmission of indications.*—After thus having registered or identified the transmitting field station in the control office by positioning the polar contacts of pilot relays 1PT to 4PT inclusive, to the positions illustrated in Fig. 1C, the remaining steps of the cycle are employed for the 35

transmission of indications from the registered station.

With the track relay picked up, as indicated in Fig. 2A, the No. 2 "on" indication condition is selected when relay FP^1 is dropped during the second "off" period, by closing a circuit for picking up relay FZ^1 which extends from (+), front contact 287 of relay TR, front contact 288 of relay IV^1 , back contact 289 of relay $3V^1$, back contact 290 of relay VP^1 , conductor 287, back contact 274 of relay FP^1 , winding of relay FZ^1 and front contact 271 of relay LO^1 to (-). With relay FZ^1 thus picked up during the second "off" period, it is stuck up throughout the following (second) 15 "on" period over a circuit including front contact 273 of relay FZ^1 and front contact 274 of relay FP^1 . Relay FZ^1 is dropped out during the third "off" period, in the event that the selection for the third "on" period requires this relay to be 20 deenergized.

With relay FZ^1 picked up throughout the second "on" period, alternating current is prevented from flowing over the line circuit to the control office during the second "on" period, which prevents the picking up of relay MFZ during the second "on" period and this condition is executed 25 during the third "off" period by completing a circuit from (B+), back contact 100 of relay MFZ , front contact 101 of relay $2E$, conductor 30 152, back contact 102 of relay F , front contact 103 of relay SA , front contact 104 of relay CF , front contact 105 of relay VP , front contact 106 of relay $2V$, conductor 148, polar contacts 147, 146, 99, and 108 of the pilot relays in their illustrated 35 positions and winding of relay IIR to (CN). Current flow over this circuit in this direction positions polar contact 150 of relay IIR to the right, which prevents the energization of lamp OS , this being an indication that the associated track section is unoccupied.

From the above examples it is believed obvious that, with track relay TR deenergized, the above described circuit for picking up relay FZ^1 is incomplete during the second "off" period, so that relay FZ^1 remains down during the second "on" period and alternating current is permitted to flow through to the control office for picking up relay MFZ during the second "on" period. Relay MFZ is stuck up throughout the third "off" 40 period and (B-) is connected to the above described circuit extending to relay IIR , which positions polar contact 150 of this relay to its left hand dotted position for energizing lamp OS , this being an indication that the associated track section is occupied.

Relay M (Fig. 2A) is illustrated to indicate how alternating current is permitted to flow or prevented from flowing through to the control office during the second "off" period. With relay M in the position shown alternating current can flow through to the office in the second "off" period because relay BZ^1 is not picked up during the first "on" period, when the second "off" selection is made by relay FP^1 closing its front contact 45 280. With relay M in its alternate dropped away position, then alternating current is prevented from flowing through to the control office. This will be understood by considering the previously described operation controlled by the first "off" condition in accordance with the connection of jumper 213. The indications in the control office controlled by this conditioning of the line during the "off" periods have not been illustrated, since it is believed obvious how these indications condition relay MBZ for positioning a polar relay

similar to relay IIR in accordance with whether (B+) or (B-) is connected to its winding through contacts selected by the four pilot relays. This (B+) or (B-) is connected to such an indication receiving relay winding through contacts selected by the four pilot relays, this (B+) and (B-) being selectively applied at contact 118 of relay MBZ .

It is also believed obvious how a relay contact may control the time of the "on" indications at steps 2 and 3 of the station stepping relay bank in the same manner above described in connection with jumper 210, for transmitting a choice of two indications in accordance with the length of the "on" periods.

Lock-out between field stations.—It may happen that changes occur at a plurality of field stations at the same time or in rapid succession, so that more than one field station will have new indications to transmit at the beginning of a cycle. In order to prevent more than one station actively associating itself with the line circuit during any particular cycle, lock-out means are provided at each station which are effective at the beginning of a cycle to select that station nearest the control office having new indications to transmit.

Assuming that a change occurs at the illustrated field station, which station is assumed to be the one nearest the control office, the dropping of relay CH closes its back contact 253 for picking up relay PB^1 , which opens the normally energized line circuit as previously described. It was previously explained how relay LO^1 is picked up during the initiating period of an indication cycle and stuck up throughout this cycle. It was also explained that relay F^1 is dropped out in response to the opening of the line circuit and when the line is reenergized, relays F^1 , FP^1 , SA^1 and SB^1 are picked up during the conditioning "on" period. The closure of front contact 264 of relay SA^1 completes a stick circuit for relay LO^1 at the illustrated station.

The opening of the line circuit effects the dropping of the F relays and the associated slow-acting PT relays at other stations farther out the line. When the line is reenergized during the conditioning "on" period, the line relays at the more distant stations are not energized because the line circuit extending outward from the illustrated station is open at back contact 221 of relay PB^1 . Since it requires the actuation of a polar contact of the line relay at a station to pick up the associated LO relay, it will be obvious that this open line circuit condition prevents the picking up of the lock-out relay at any inferior station (beyond the one illustrated) which attempts to actively associate itself with the line.

When relay PB^1 at the preferred station is dropped in response to the picking up of relay SA^1 , as previously described, the pick-up circuit of relay LO^1 is opened at front contact 260, but at this station relay LO^1 remains energized by means of its stick circuit. At a more distant station having its PB relay picked up, the opening of the contact of this relay, corresponding to contact 260, opens the pick-up circuit of the associated lock-out relay before the line is reenergized, so that the lock-out relay at the non-preferred station is prevented from picking up during this cycle. It will be recalled that when relay PB^1 (and similar relays at more distant stations attempting to transmit), is dropped out during the conditioning "on" period, this relay is not again picked up during this cycle.

When relay PT¹ drops out during the conditioning "on" period, the continuity of the line circuit from the preferred transmitting station is established toward the control office by way of front contact 221 of relay PB¹, back contact 291 of relay PT¹, back contact 292 of relay SB¹ and resistance 3R¹. When relay PB¹ drops out during the conditioning "on" period, then the continuity of the line circuit is completed by way of back contacts 221 and 220 through to the end of the line, but at this time it is too late for a station farther out the line to pick up its LO relay by way of a contact closed by its line relay similar to contact 204 of relay F¹, because the PB relay at this more distant station will be down and the circuit to the associated lock-out relay will be open at a contact similar to 260.

At the more distant station assumed to have indications ready to transmit, the line and line repeating relays will be energized during the following cycle because the line circuit through all the stations to the end is complete. At the more distant station however, the step-by-step relay operation will be ineffective as soon as the control code (phantom or otherwise) drops out the SO relay, because of an open front contact similar to 266 of relay SO and an open front contact similar to 267 of relay LO¹.

Although the lock-out feature has been explained with reference to the first station having preference over a more distant station, it will be understood that similar conditions may exist between other preferred and non-preferred stations in the system. It is believed however that the above explanation is sufficient for an understanding of all such combinations, remembering that in each case the station nearest the control office which picks up its PB relay effects the picking up of the associated lock-out relay because the line relay at this station can be energized, while the line relays beyond this station cannot be energized.

Two-way transmission.—It has been pointed out that control and indication cycles may each occur separately or simultaneously. The operations for control and indication cycles alone have been described and it will now be pointed out how the system functions when controls and indications are transmitted during the same cycle. An actuation of the starting button in the control office results in the picking up of the CD relay. Relay C may be picked up at the beginning of a cycle any time up to the end of the period marked off by the picking up of relay SB and the consequent opening of its back contact 44. If a field station has initiated a start, which results in the picking up of relay CF as previously described, front contact 149 of relay CF bridges back contact 43 of relay OC so that relay C may be picked up any time before the picking up of relay SB and when it is picked up it will be stuck up throughout the cycle by means of a stick circuit which also sticks up relay CF throughout the cycle.

With relays CD and C picked up due to a control office start being effective and with relay CF picked up due to a field station start being effective, the line circuit is conditioned by changing its energization from (−) to (+) during the conditioning "on" period as previously described. This is because the circuit for selectively picking up relay PC or relay NC extends through front contact 49 of relay C. Under this condition, the lock-out relay associated with the transmitting field station will be picked up and the (+) im-

pulse applied to the line circuit during the conditioning "on" period picks up all the SO and SOS relays at all field stations, as previously described, so that stepping at all stations will be started.

The stepping and impulsing operations will be effected as before and the character of the impulses applied to the line circuit, as well as the lengths of the "off" periods, will be determined by the particular CD relay which is picked up for selecting the desired station and for transmitting controls thereto in the manner previously described. Since the lock-out relay at a particular station having indications to transmit is also picked up, stepping will continue at this station in the event that it is not the station selected for controls, because of the closure of a front contact similar to contact 267 of relay LO¹ of Fig. 2.

The resulting cycle of operations is thus the same, insofar as the transmission of control codes over the line circuit is concerned, as was previously described in connection with a control cycle alone. Similarly the resulting operations during the cycle, insofar as the control of the lengths of the "on" periods and the conditioning of the line circuit by preventing or permitting alternating current to flow through to the control office in accordance with the station to be identified and the indications transmitted therefrom, is the same as described for a cycle during which indications alone were transmitted. It is believed that the above brief explanation is sufficient to clearly indicate that, since the transmission of controls and the transmission of indications are effected by the separate and distant conditioning of the line circuit, these transmissions may be combined and brought about during a single cycle of operations in the manner previously pointed out.

Description of modification.—The modification illustrated in abbreviated form Fig. 3 indicates a second method for applying alternating current to the line circuit. The control office arrangement already shown and described will be slightly modified to work in connection with the Fig. 3 modification and the field circuits will be the same as previously shown and described, with the exceptions illustrated in Fig. 3.

In this modification it is proposed to provide a D. C. to A. C. converter at each field station, started into operation by the picking up of the associated lock-out relay, when this station is to transmit indications, by the closure of a front contact similar to contact 325 of relay LO³. It will be understood that this converter is provided at the end station as well as other stations, but since the circuit arrangement is the same at all stations it is believed unnecessary to duplicate the showing. The only difference between the end station and other stations is that the line conductors are tied together at the end station to form a complete loop circuit through all stations.

The inductance 1IN¹ illustrated in Fig. 2 has been replaced by transformer TF³ in Fig. 3, so that the alternating current is applied to the line circuit at each transmitting station during the "on" and "off" periods by the operation of the contacts of the FP³, FZ³, and BZ³ relays in a manner just opposite to that described and illustrated in Fig. 2. In other words a transmitting field station applies or does not apply alternating current to the line circuit, in accordance with whether the FZ or BZ relay is up or not

in accordance with the code to be transmitted, instead of having the transmitting field station prevent or permit the flow of alternating current to go through to the control office in accordance with the code to be transmitted. The operation of the Fig. 3 modification may thus be understood without further description, by analogy to the previously described operation of the field station illustrated in Figs. 2, 2A, and 2B.

10 It will be understood that this inverse arrangement of transmission in the Fig. 3 modification requires a compensating arrangement in the office, such as reversing the (B+) and (B-) potentials at contacts 100 and 118 of relays MFZ and MBZ, 15 or a rearrangement of the circuits through the contacts of pilot relays 1PT, 2PT, and 4PT.

Having thus described a centralized traffic controlling system as one form and a modification thereof, it is desired to be understood that these 20 forms of the present invention are selected to facilitate in the disclosure rather than to limit the number of forms which the invention may assume and it is further to be understood that various modifications, adaptations and alterations 25 may be applied to the specific forms shown to meet the requirements of practice without departing from the spirit of the invention as limited by the appended claims.

What I claim is:—

30 1. A centralized traffic controlling system for simultaneously transmitting out-bound controls and in-bound indications between a control office and a field station comprising; a single line circuit connecting the control office and the field station; means in the office for determining the polarity of each impulse of a series of time-spaced direct current impulses applied to said line circuit, each direct current impulse being of a polarity selected in accordance with the controls to 35 be transmitted; means at said field station for varying the time duration of each of said impulses in accordance with a portion of the indications to be transmitted; and means at said field station for applying or not applying alternating current to said line circuit concomitantly with the 40 application of said direct current impulses in accordance with the other portion of the indications to be transmitted.

2. A centralized traffic controlling system for 45 simultaneously transmitting out-bound controls and in-bound indications between a control office and a field station comprising; a single line circuit connecting the control office and the field station; means in the office for determining the polarity of each impulse of a series of time spaced direct current impulses applied to said line circuit, each direct current impulse being of a polarity selected in accordance with a portion of the controls to be transmitted; means in the office 50 for determining the time of duration of the time spaces between said direct current impulses, each time space being of a length selected in accordance with another portion of the controls to be transmitted; means at said field station for varying the time duration of each of said impulses in accordance with a portion of the indications to be transmitted; and means at said field station for applying or not applying alternating current to said line circuit concomitantly with the 55 application of said direct current impulses in accordance with another portion of the indications to be transmitted.

3. A centralized traffic controlling system for 60 simultaneously transmitting out-bound controls and in-bound indications between a control of-

fice and a field station comprising; a single line circuit connecting the control office and the field station; means in the office for determining the polarity of each impulse of a series of time spaced direct current impulses applied to said line circuit, each direct current impulse being of a polarity selected in accordance with a portion of the controls to be transmitted; means in the office for determining the time of duration of the time spaces between said direct current impulses, 10 each time space being of a length selected in accordance with another portion of the controls to be transmitted; means at said field station for varying the time duration of each of said impulses in accordance with a portion of the indications 15 to be transmitted; and means at said field station for applying or not applying alternating current to said line circuit during the time spaces between said direct current impulses in accordance with still another portion of the indications to be 20 transmitted.

4. In a remote control system, a control office and a field station connected by a line circuit, means at said office for applying time spaced direct current impulses to said line circuit, means 25 at said office for transmitting control codes to said station by marking said impulses with distinctive polarities, an alternating current source at said field station for the purpose of applying alternating current to said line circuit, means at 30 said field station for transmitting indication codes to said office by preventing or permitting said alternating current to flow over said line circuit to said office concomitantly with the flow of said direct current impulses, said means including 35 contacts which by closing shunt said alternating current source and other contacts which by opening restrict the flow of alternating current in that portion of said line circuit extending towards said office, and means at said field station 40 and at said office for simultaneously decoding said control and said indication codes respectively.

5. In a remote control system, a control office and a plurality of field stations connected by a line circuit, means at said office for applying time spaced direct current impulses to said line circuit, means at said office for transmitting control codes to said stations by marking said impulses with distinctive polarities, a source of alternating current in said line circuit at the most remote field station, means including contacts in said line circuit at one of said field stations between said source and said office for transmitting indication codes to said office by preventing 45 or permitting said alternating current to flow over said line circuit to said office concomitantly with the flow of said direct current impulses, and means at said field station and at said office for simultaneously decoding said control and said indication codes respectively.

6. In a remote control system, a control office and a field station connected by a line circuit, means at said office for applying time spaced direct current impulses to said line circuit, means 50 at said office for transmitting control codes to said station by marking said impulses with distinctive polarities, means at said field station for applying alternating current to said line circuit, means at said field station for transmitting indication codes to said office by preventing or permitting said alternating current to flow over said line circuit to said office concomitantly with the flow of said direct current impulses and the time spaces between, and means at said field sta- 55 60 65 70 75

tion and at said office for simultaneously decoding said control and said indication codes respectively.

7. In a remote control system, a control office and a plurality of field stations connected by a line circuit, step-by-step mechanisms at said office and at said stations, means at said office for applying a plurality of time spaced impulses to said line circuit for effecting an operating cycle of said mechanisms, means at said office for distinctively characterizing each of said impulses and the time spaces therebetween, means at each of said stations for varying the lengths of said impulses, means at each of said stations selectively responsive to the character of said impulses and said time spaces for selecting a first field station during an operating cycle of said mechanisms, and means at said office selectively responsive to the lengths of said impulses for registering said first station in said office during said operating cycle.

8. In a remote control system, a control office and a plurality of field stations connected by a line circuit, step-by-step mechanisms at said office and at said stations, means at said office for applying a plurality of time spaced impulses to said line circuit for effecting an operating cycle of said mechanisms, means at said office for distinctively characterizing each of said impulses and the time spaces therebetween, means at each of said stations for varying the lengths of said impulses, means at each of said stations selectively responsive to the character of said impulses and said time spaces for selecting a first field station during an operating cycle of said mechanisms, and means at said office selectively responsive to the lengths of said impulses for registering a second station in said office during said operating cycle.

40 9. In a remote control system, a control office and a plurality of field stations connected by a line circuit, step-by-step mechanisms at said office and at said stations, signalling devices at said office and at said stations, means at said office for applying a plurality of time spaced impulses to said line circuit for effecting an operating cycle of said mechanisms, means at said office for distinctively characterizing each of said impulses and the time spaces therebetween, means at each of said stations for varying the lengths of said impulses, means at each of said stations selectively responsive to the character of said impulses and said time spaces for selecting a first field station and for operating the signalling devices thereat during an operating cycle of said mechanisms, and means at said office selectively responsive to the lengths of said impulses for registering said first station in said office and for operating its associated signalling devices.

60 10. In a remote control system, a control office and a plurality of field stations connected by a line circuit, step-by-step mechanisms at said office and at said stations, signalling devices at said office and at said stations, means at said office for applying a plurality of time spaced impulses to said line circuit for effecting an operating cycle of said mechanisms, means at said office for distinctively characterizing each of said impulses and the time spaces therebetween, means at each of said stations for varying the lengths of said impulses, means at each of said stations selectively responsive to the character of said impulses and said time spaces for selecting a first field station and for operating the signal-

ling devices thereat during an operating cycle of said mechanisms, and means at said office selectively responsive to the lengths of said impulses for registering a second station in said office and for operating its associated signalling devices. 5

11. In a remote control system, a control office and a field station connected by a line circuit, step-by-step mechanisms at said office and at said station, means for operating said mechanisms through a cycle in synchronism by energizing said line circuit with a plurality of time spaced direct current impulses, means at said office for making said direct current impulses normally long, means for applying alternating current to said line circuit during said cycle, means at said station for transmitting first code messages to said office by controlling said line circuit to change at least one of said normally long impulses to abnormally short impulses, 10 means at said station for transmitting second code messages to said office by permitting or preventing said alternating current to flow over said line circuit during said cycle, a first and a second registering relay in said office, means selectively 15 responsive to said long and said short impulses for distinctively operating said first registering relay during said cycle, means selectively responsive to the presence or absence of alternating current flow over said line circuit for distinctively operating said second registering relay during said cycle, and means controlled by the distinctive operation of said registering relays for registering said first and said second code messages in said office. 20

35 12. In a remote control system, a control office and a field station connected by a line circuit, step-by-step mechanisms at said office and at said station, means for operating said mechanisms through a cycle in synchronism by energizing said line circuit with a plurality of time spaced direct current impulses, means at said office for making said direct current impulses normally long, means for applying alternating current to said line circuit during said cycle, means at said station for transmitting first code messages to said office by controlling said line circuit to change said normally long impulses to abnormally short impulses, means at said station for transmitting second code messages to said office by permitting or preventing said alternating current to flow over said line circuit during said cycle concomitantly with said direct current impulses and the time spaces between, a first and a second registering relay in said office, means selectively responsive to said long and said short impulses for distinctively operating said first registering relay during said cycle, means selectively responsive to the presence or absence of alternating current flow over said line circuit for distinctively operating said second registering relay during said cycle, and means controlled by the distinctive operation of said registering relays for registering said first and said second code messages in said office. 40

50 13. In a remote control system; a control office and a field station connected by a normally energized line circuit; means at said office for de-energizing and energizing said line circuit to form a series of substantially equally time spaced direct current impulses of equal duration; step-by-step mechanisms at said office and at said station operated in synchronism by said direct current impulses; code forming means at said station operable successively by said mechanism to change said direct current impulses to a series 55

substantially equally time spaced, of unequal durations and having during certain impulses alternating current superimposed thereon; and means at said office for selectively registering said unequal direct current impulse durations and the presence of said superimposed alternating current on said direct current impulses.

14. In a remote control system, a control office and a plurality of field stations all interconnected by a line circuit, code transmitting means at said office for energizing said line circuit with a plurality of different series of time spaced direct current impulses, a first indication transmitting means at each field station capable of varying the lengths of said direct current impulses to distinctively condition said line circuit for each impulse, a second indication transmitting means at each field station capable of superimposing alternating current on some of said direct current impulses to further distinctively condition said line circuit for each impulse, means responsive to the distinctive conditioning of said line circuit by said first and said second indication transmitting means for selectively registering said stations in said office, and means for rendering effective the indication transmitting means at only one station during any one particular series of direct current impulses applied to said line circuit.

15. In a remote control system, a control office and a field station connected by a line circuit, a series of stepping relays at said office and at said station, means for operating said stepping relays in synchronism by a series of time spaced impulses of distinctive character applied to said line circuit, a first character selecting relay device for selectively determining the character of each impulse, a second character selecting relay device for selectively determining the length of each time space between succeeding impulses, means controlled by the stepping relays at the office for completing circuits for said first and said second character selecting relay devices during the time spaces between said impulses, and means controlled by the stepping relays at said station for selectively recording the character of each impulse and the lengths of time spaces between.

16. In a remote control system, a control office and a field station connected by a line circuit, means at said office for applying time spaced direct current impulses to said line circuit, means at said office for transmitting control codes to said station by marking said impulses with distinctive characters, means at said station for applying alternating current to said line circuit, means at said station for transmitting alternating current indication codes to said office by preventing or permitting said alternating current to flow over said line circuit to said office, means at said station for decoding said control codes, a vacuum tube detector in said office, means controlled by said vacuum tube detector for detecting the flow of alternating current over said line circuit to said office, means controlled by said vacuum tube detector for translating said alternating current indication codes to direct current indication codes, and means in said office for decoding said indication codes.

17. In a remote control system, a control office and a field station connected by a line circuit, means at said office for applying time spaced direct current impulses to said line circuit, means at said office for transmitting control codes to said station by marking said impulses with distinctive characters, means at said station for ap-

plying alternating current to said line circuit, means at said station for transmitting indication codes to said office simultaneously with the transmission of said control codes by preventing or permitting said alternating current to flow over said line circuit to said office, means at said station for decoding said control codes, a vacuum tube detector in said office, means controlled by said vacuum tube detector for detecting the flow of alternating current over said line circuit to said office, means controlled by said vacuum tube detector for translating said indication codes from alternating current indication codes to direct current indication codes, and means in said office for decoding said indication codes.

18. In a remote control system, a control office and a field station connected by a line circuit, means at said office for applying time spaced direct current impulses to said line circuit, means at said office for transmitting control codes to said station by marking said impulses with distinctive characters, means at said station for applying alternating current to said line circuit, means at said station for transmitting indication codes to said office by preventing or permitting said alternating current to flow over said line circuit to said office concomitantly with said direct current impulses and said time spaces, means at said station for decoding said control codes, a vacuum tube detector in said office, means controlled by said vacuum tube detector for detecting the flow of alternating current over said line circuit to said office, means controlled by said vacuum tube detector for translating said indication codes from alternating current indication codes to direct current indication codes, and means in said office for decoding said indication codes.

19. In a remote control system, a control office and a plurality of field stations connected by a single line circuit, step-by-step mechanisms at said office and at said stations, means for stepping said mechanisms through a cycle in synchronism by a series of time spaced direct current impulses applied to said line circuit, means at each station for controlling the lengths of said direct current impulses to form a portion of a composite code, means at each station for superimposing or not superimposing alternating current on said direct current impulses to form the remaining portion of said composite code, and means controlled by said composite code for identifying in said office the particular station which effects the forming of said composite code.

20. In a remote control system, a control office and a plurality of field stations connected by a single line circuit, step-by-step mechanisms at said office and at said stations, means for stepping said mechanisms through a cycle in synchronism by a series of time spaced direct current impulses applied to said line circuit, means at each station for controlling the lengths of said direct current impulses to form a portion of a composite code, means at each station for superimposing or not superimposing alternating current on said direct current impulses to form another portion of said composite code, means at each station for applying or not applying alternating current to said line circuit during the time spaces between said impulses to form the remaining portion of said composite code, and means controlled by said composite code for identifying in said office the particular station which effects the forming of said composite code.

21. In a remote control system, a control office

75

and a plurality of field stations connected by a single line circuit, step-by-step mechanisms at said office and at said stations, means for stepping said mechanism through a cycle in synchronism by a series of time spaced direct current impulses applied to said line circuit, means in said office for opening said line circuit for causing at least one of said impulses to be normally long, a first transmitting means at one of said stations 5 for opening said line circuit before it is opened in the office for causing at least one of said impulses to be abnormally short, a second transmitting means at said one of said stations for superimposing or not superimposing alternating current on at least one of said impulses, and means 10 selectively responsive to a combination of said long and short impulses and said superimposed alternating current for registering said one of said stations in said office to the exclusion of all 15 other stations of said plurality.

22. In a remote control system, a control office and a plurality of field stations connected by a single line circuit, step-by-step mechanisms at said office and at said stations, means for stepping said mechanism through a cycle in synchronism by a series of time spaced direct current impulses applied to said line circuit, means in said office for opening said line circuit for causing at least one of said impulses to be normally long, a first transmitting means at one of said stations for opening said line circuit before it is opened in the office for causing at least one of said impulses to be abnormally short, a second transmitting means at said one of said stations for superimposing or not superimposing alternating current on at least one of said impulses and an adjoining time space, and means 25 selectively responsive to a combination of said long and short impulses and time spaces and said superimposed alternating current for registering said one of said stations in said office to the exclusion of all other stations of said plurality.

23. In a remote control system, a control office and a plurality of field stations connected by a single line circuit, step-by-step mechanisms at said office and at said stations, means for stepping said mechanism through a cycle in synchronism by a series of time spaced direct current impulses applied to said line circuit, means in said office for opening said line circuit for causing at least one of said impulses to be normally long, a first transmitting means at one of said stations for opening said line circuit before it is opened in the office for causing at least one of said impulses to be abnormally short, a second transmitting means at said one of said stations for superimposing or not superimposing alternating current on at least one of said impulses, 40 means selectively responsive to a combination of said long and short impulses and said superimposed alternating current for registering said one of said stations in said office to the exclusion of all other stations of said plurality, and lock-out means operable at the start of said cycle for rendering the transmitting means at said one of said stations effective and at all other stations of said plurality ineffective during said cycle.

24. In a remote control system, a receiver comprising a line relay, a plurality of stepping relays, means for actuating said stepping relays sequentially in response to repeated operations of said line relay by a series of time spaced impulses of direct current, means for determining 45 the duration of selected ones of said impulses,

means for superimposing alternating current on selected ones of said impulses, a message receiving relay controlled by said superimposed alternating current, a plurality of indication relays for each of said selected impulses, means controlled by said line relay and said stepping relays and rendered effective at the termination of each impulse for causing one of the corresponding indication relays to be actuated to one position or another in accordance with the relative duration of the impulse, and means controlled by said message receiving relay and said stepping relays and rendered effective during the operation of said line relay by selected ones of said impulses for causing another of the corresponding indication relays to be actuated to one position or another in accordance with the presence or absence of superimposed alternating current on the direct current impulse.

25. In a remote control system, a receiver comprising a line relay, a plurality of stepping relays, means for actuating said stepping relays sequentially in response to repeated operations of said line relay by a series of time spaced impulses of direct current, means for determining the duration of selected ones of said impulses, means for superimposing alternating current on selected ones of said impulses, a message receiving relay controlled by said superimposed alternating current, a plurality of indication relays for each of said selected impulses, means controlled by said line relay and said stepping relays and rendered effective at the termination of each impulse for causing one of the corresponding indication relays to be actuated to one position or another in accordance with the relative duration of the impulse, means controlled by said message receiving relay and said stepping relays and rendered effective during the operation of said line relay by selected ones of said impulses for causing another of the corresponding indication relays to be actuated to one position or another in accordance with the presence or absence of superimposed alternating current on the direct current impulse, and means for translating said superimposed alternating current into direct current for operating said message receiving relay.

26. In a remote control system, a control office and a plurality of field stations connected by a line circuit, means at said office for applying time spaced direct current impulses to said line circuit, means at said office for transmitting control codes to said stations by marking said impulses with distinctive polarities, a source of alternating current included in said line circuit at the most distant one of said field stations, means including two contacts at another of said field stations for transmitting indication codes to said office by preventing or permitting said alternating current to flow over said line circuit to said office concomitantly with the flow of said direct current impulses, one of said contacts opening that portion of the line circuit extending toward said office for the flow of alternating current and the other contact shunting said line circuit at that station for the flow of alternating current to effect such preventing, and means at said field station and at said office for simultaneously decoding said control and said indication codes respectively.

27. In a remote control system, a control office and a plurality of field stations connected by a line circuit, means at said office for applying time spaced direct current impulses to said line circuit, means at said office for transmitting 75

control codes to said stations by marking said impulses with distinctive polarities, a source of alternating current included in said line circuit at the most distant field station, means at another of said field stations for transmitting indication codes to said office by intermittently preventing or permitting said alternating current to flow over said line circuit to said office once for each impulse, said last mentioned means 10 preventing the flow of alternating current by shunting said line circuit for the flow of alternating current without shunting it for the flow of direct current, and means at said field station and at said office for simultaneously decoding said control and said indication codes respectively.

28. In a remote control system, a control office and a field station connected by a line circuit, a series of stepping relays at said office and at said 20 station, means for operating said stepping relays in synchronism by a series of time spaced impulses of distinctive character applied to said line circuit, a first character selecting relay device for selectively determining the character of each 25 impulse, a second character selecting relay device for selectively determining the length of each time space between succeeding impulses, means controlled by the stepping relays at the office for completing circuits for said first and 30 said second character selecting relay devices during the time spaces between said impulses, and a decoding stick relay controlled in part by said stepping relays and having an energizing stick circuit broken only during each series of impulses 35 when the characters of these impulses and their succeeding time spaces are not in agreement with the code for that station for controlling apparatus at that station.

29. In a remote control system, a control office and a plurality of field stations connected 40

by a single line circuit, step-by-step mechanisms at said office and at said stations, means for stepping said mechanisms through a cycle in synchronism by a series of time spaced direct current impulses applied to said line circuit, 5 means at each station for controlling the lengths of said direct current impulses to form a portion of a composite code, means including a source of alternating current in said line circuit at the last field station and apparatus at a particular field station for superimposing or not superimposing alternating current on said direct current impulses to form the remaining portion 10 of said composite code, and means controlled by said composite code for identifying in said office 15 the particular station which effects the forming of said composite code.

30. In a remote control system, a control office and a plurality of field stations connected by a single line circuit, step-by-step mechanisms at 20 said office and at said stations, means for stepping said mechanism through a cycle in synchronism by a series of time spaced direct current impulses applied to said line circuit, means in said office for intermittently opening said line circuit for 25 causing said impulses to be normally long, a first transmitting means at one of said stations for opening said line circuit before it is opened in the office for causing at least one of said impulses to be abnormally short, a second transmitting 30 means at said one of said stations for superimposing alternating current on the line circuit for at least one of said impulses or one of the time spaces between such impulses, and means selectively responsive to a combination of said long 35 and short impulses and said superimposed alternating current for registering said one of said stations in said office to the exclusion of all other stations of said plurality.

WILLIAM D. HAILES. 40
